UNITED STATES PATENT OFFICE.

MARCO GIOVANNI ZONGARO, OF PORTLAND, OREGON.

WORK SUPPORT FOR GRINDING MACHINES.

Application filed September 19, 1921. Serial No. 501,680.

To all whom it may concern:

Be it known that I, MARCO G. ZONGARO, a citizen of the United States, residing at Portland, in the county of Multnomah and 5 State of Oregon, have invented certain new and useful Improvements in Work Supports for Grinding Machines; and I do declare the following to be a full, clear, and exact description of the invention 10 such as will enable others skilled in the art to which it appertains to make and use the same.

My invention relates to improvements in grinding machines and more particularly 15 to those which commonly comprise an arbor and an emery wheel, used extensively in machine shop, foundries and the like, for grinding castings. About sixty-five per cent of the castings can be more 20 effectively ground if some form of work support is provided adjacent the periphery of the grinding wheel but on the other hand, there are a great number of castings which cannot be ground if such a work 25 support is permanently located adjacent said wheel, that is adjacent the periphery thereof. It is therefore the principal object of my invention to provide a comparatively simple and inexpensive, yet a highly 30 efficient and reliable work support which is attached in a unique manner to the usual grinding machine and which can be swung either downwardly into operative position or upwardly into an inactive position at 35 which it will be entirely out of the way when grinding certain forms of castings.

With the foregoing in view, the invention resides in the novel construction and arrangement of parts hereinafter described 40 and claimed, the descriptive matter being supplemented by the accompanying drawings.

Figures 1 and 2 are respectively a top plan view and a side elevation of a grinding machine equipped with my invention.

Figure 3 is a detail vertical sectional view as indicated by line 3-3 of Fig. 1.

Figure 4 is a vertical transverse section on line 4-4 of Fig. 2.

Figure 5 is a detail horizontal section on line 5-5 of Fig. 4.

Figures 6 and 7 are respectively a side elevation and an edge view of the mounting and adjusting means of the work sup- 55 port.

Figures 8 and 9 are elevations of the adjusting and mounting elements shown in Figs. 6 and 7.

I have illustrated my invention in connection with a common type of grinding 60 machine which includes a suitable base 1, end plates 2 rising from said base and connected by a longitudinal web 3, bearings 4 supported by said end plates and web, a driven shaft or arbor 5 rotatably mounted 65 in the bearings, and a grinding wheel 6 on said shaft. Usually two grinding wheels are employed, one on each end of the shaft 5, but for purposes of illustration I have only shown one and while my 70 invention is disclosed only in connection with this one grinding wheel, it will be of course understood that it may if desired be used in connection with both wheels.

Interposed between the grinding wheel 75 6 and one of the end plates 2, is a flat attaching plate 7 having an opening 8 near its upper end through which the shaft 5 passes rotatably, the lower end of said plate being preferably supported on a lug 9 80 formed on the end plate 2, in order that its weight and the weight of the parts carried thereby, will not act directly downwardly on the shaft, producing unnecessary strain or wear. I intend that the plate 85 7 shall have slight pivotal adjustment about the shaft 5 and for effecting this adjustment, I pass a suitable number of set screws 10 through a lateral flange 11 which is provided on one edge of said plate, said 90 set screws bearing against the edge of the end plate 2 so that when they are either tightened or loosened, the plate will swing transversely of the machine. This is desirable for a purpose which will be more 95 apparent as the description proceeds.

Any suitable means may be employed to lock the plate 7 in adjusted position and to secure it tightly in place, but for this purpose I prefer to pass a plurality of cap 100 screws 12 through slots 13 in the end plate 2, said cap screws being threaded into the plate 7 so that when they are tightened, this plate will be clamped tightly against the end plate 2.

The plate 7 is by preference provided on its outer side with an integral boss 14 through which the opening 8 extends, and above this boss, the upper end of the plate 110 is curved as indicated at 15, on a line con-

centric with said boss, this curved edge being provided with an outwardly extending flange 16 whose ends form shoulders 17 and 18 for a purpose to appear. Also, the 5 rear end of the curved edge 15 is provided with a stop shoulder 19 and below this shoulder, the rear edge of the plate 7 is equipped with a laterally extending L-shaped arm 20 by means of which a 10 wheel guarding hood (not shown) may be attached.

Pivottally mounted on the boss 14, is a bearing 22 which is provided on its lower side with a transversely extending guide 23 15 of hollow formation. An arm 24 is slidably received in guide 23 and is provided on its outer end with a lateral extension 25 constituting a work support for disposition at the periphery of the wheel 6, and by shifting the arm 24 inwardly as the wheel wears 20 down, the work support may be at all times positioned in close proximity to said wheel for obtaining the best results. A set screw 27 may well be threaded through said guide 25 into contact with the arm 24 in order to lock said arm in any position to which it may be adjusted.

The bearing 22 is provided with a hand lever 28 which is preferably integral there- 30 with and provided with offset ends as shown, the intermediate portion 29 of said lever being disposed adjacent the curved edge 15 of the plate 7 and being provided with an opening 30 through which a spring-pressed 35 pawl 31 passes slidably, said pawl being co-operable with the shoulder 18 to hold the several parts in position to properly dispose the work rest 25 at the periphery of the wheel 8. The pawl 31 also co-acts with the 40 shoulder 17 to hold the lever 28 against movement when it is raised for the purpose of positioning the work rest 25 above the wheel so that it will be entirely out of the way when grinding certain types of cast- 45 ings. When the lever is in the last named position, its intermediate portion 29 strikes the stop shoulder 19 so that the operator need not have any difficulty in stopping the lever at the proper point, but need only force said 50 lever rearwardly as far as possible, whereupon the pawl 31 is forced by its spring 32, behind the shoulder 17. When the lever is moved forwardly, the several parts actuated thereby, are limited in movement by contact 55 of the rear end of the guide 23 with the lower edge of the arm 20 as seen in Fig. 4, although it will be understood that any other suitable stop could be provided.

For the purpose of releasing the pawl 31, 60 I mount a suitable thumb lever 33 on the lever 28 and connect the same with said pawl in a common manner.

The device is easy to install and will be highly efficient and in every way desirable. 65 When grinding castings which require the

use of a work support, the lever 28 is swung forwardly and downwardly, thereby positioning the rest 25 at an operative point so as to greatly expedite the grinding operation. However, when other forms of cast- 70 ings are to be ground, such as those having concave surfaces to be reached by the grinding wheel, the lever 28 is forced rearwardly and the pawl 31 is engaged with the shoulder 17 to hold the several parts in this position. As the wheel 6 wears down from continual use, the set screw 27 is loosened and the arm 24 is adjusted rearwardly in the guide 23 to insure proper disposition of the work rest 25 with respect to the wheel 6. 80 This having been done, the set screw 27 is again tightened. Whenever it is necessary to slightly raise or lower the rest 25 when it is held in an operative position by the pawl 31, the cap screws 12 are loosened, the set screws 10 are operated to pivotally move the plate 7 and all parts carried thereby about the shaft 5, and said cap screws are again tightened.

Since probably the best results may be obtained from the details shown, such details may be followed, but within the scope of the invention as claimed, numerous minor changes may of course be made.

I claim:

1. A work support comprising an arm adapted to pivot about the arbor of a grinding wheel, said arm having a work rest, means for pivotally mounting said arm at one side of the wheel, a handle connected 100 with said arm for swinging it downwardly to operatively position the work support or upwardly to move said work support to an inactive position, means for holding said arm, and hand-operated means on said handle for controlling said holding means.

2. A work support comprising an arm adapted to pivot about the arbor of a grinding wheel, said arm having a work rest, means for pivotally mounting said arm at 110 one side of the wheel, a hand lever rigidly extending from said arm for swinging it downwardly to operatively position the work support or upwardly to move said work support to an inactive position, means for holding said arm, and hand operated means on said handle for controlling said holding means.

3. A work support comprising a bearing adapted to pivot about the arbor of a grinding wheel, said bearing having a transversely extending guide of hollow formation, an arm slidably in said guide and adapted to be disposed at one side of the grinding wheel, said arm having a work 120 rest, means for normally holding said arm against sliding in said guide, a hand lever extending rigidly from said bearing, a hand-released pawl carried by said lever, and means cooperable with said pawl to hold the 125 130

bearing, the arm and the work rest in a pre-determined position.

4. A work support comprising a plate having an opening to receive the arbor of a grinding wheel, means for securing said plate to a fixed part of a grinding machine of which the wheel forms a part, an arm pivotally mounted on said plate and carrying a work support, and co-acting means on 10 said plate and arm for holding the latter in a predetermined position.

5. A work support comprising a plate having an outstanding lateral boss of cylindrical form and provided with an opening 15 extending through said boss to receive the arbor of a grinding wheel, means for securing said plate to a fixed part of a grinding machine of which the wheel forms a part, an arm having an opening receiving said 20 cylindrical boss whereby said arm may have pivotal movement upon said plate, said arm being provided with a work rest, a hand lever rigid with said arm and carrying a hand released pawl, and a shoulder on said

plate co-operable with said pawl to lock said 25 lever.

6. The combination with a grinding machine including an arbor, a grinding wheel at one end of said arbor, a bearing spaced from said wheel and supporting said arbor, 30 and a vertical end plate supporting said bearing; of an attaching plate resting flat against said vertical end plate, one of said plates having a transverse slot, a fastener passing through said slot and engaging the 35 other plate to clamp the two plates tightly together, an adjusting screw carried by said attaching plate and engaging the edge of said end plate to pivotally adjust said attaching plate about the arbor, a work supporting device pivotally mounted on said attaching plate, and co-acting means on said work supporting device and said attaching device for holding the former in a predetermined position. 40

In testimony whereof I have hereunto set 45 my hand.

MARCO GIOVANNI ZONGARO.
